UNITED STATES PATENT OFFICE.

REINHOLD KRUMMING, OF MILWAUKEE, WISCONSIN.

TEMPORARY BINDER OR LOOSE-SHEET HOLDER.

1,125,126.

Specification of Letters Patent.

Patented Jan. 19, 1915.

Application filed January 6, 1913. Serial No. 740,448.

To all whom it may concern:

Be it known that I, REINHOLD KRUMMING, a citizen of the United States, residing at the city of Milwaukee, county of Milwaukee, and State of Wisconsin, have invented certain new and useful Improvements in Temporary Binders or Loose-Sheet Holders, of which the following is a specification.

10 This invention relates to improvements in temporary binders or loose sheet holders.

The main objects of this invention are, first, to provide in a temporary binder or loose sheet holder of the post type, an improved securing means for the adjustable binding or clamping member. Second, to provide in a binder of the post type, an improved clutch securing mechanism for the adjustable binding member, which is simple 20 in structure and not likely to get out of order in use, and one which is simple and easy to operate.

Further objects, and objects relating to structural details, will definitely appear 25 from the detailed description to follow.

I accomplish the objects of my invention by the devices and means described in the following specification.

The invention is clearly defined and 30 pointed out in the claims.

A structure which is a preferred embodiment of my invention is clearly illustrated in the accompanying drawing forming a part of this specification, in which:

35 Figure I is a plan view of a structure embodying the features of my invention. Fig. II is a detail longitudinal section taken on a line corresponding to line 2—2 of Fig. I. Fig. III is a transverse section 40 taken on a line corresponding to line 3—3 of Fig. I, the leaves being omitted. Fig. IV is a perspective view of one of the clutch control slides or members. Fig. V is a detail section taken on a line corresponding 45 to line 5—5 of Fig. III, showing structural details of the clamping member.

In the drawing, similar reference characters refer to similar parts throughout the several views, and the sectional views are taken looking in the direction of the little arrows at the ends of the section lines.

50 Referring to the drawing, the binding pins or posts 1 are mounted upon the bar 2, which, in the structure illustrated, is rigidly secured to the cover 3. The adjustable clamping member illustrated, consists of

the bar 5 and the channeled housing piece 6, mounted on the bar. The housing piece is preferably secured by turning the ends of the top of the housing down between its sides, and arranging the tongue-like projections 7 through holes 8 provided therefor in the bar. The clamping member is transversely slotted to provide post engaging openings 9, which open at the rear side of 65 the clamping member so that it can be slipped onto the posts. A clutch spring 10 is secured to the bar 5 between the posts so that its ends project into the post openings to engage the posts. The clutch is controlled by the slides 11 which are arranged in the housing piece to engage the ends of the spring. These clutch control slides are preferably formed of pieces of sheet metal folded, as shown in Fig. IV, and provided 70 with L-shaped slots 12 adapted to register with the post openings 9 when the slides are in their releasing position, and to close said openings when the slides are in their locking position. The lower arms of the slides 80 are provided with downward cam portions 13 engaged under the ends of the clutch spring. See Fig. III. The upper arms of the slides are provided with catch lugs 14 adapted to coact with the slots. 85

The slides are supported on the stems 15 of the finger pieces 16 which are arranged through longitudinal slots 17 in the housing member 6. The ends of the slots serve as stops to limit the movement of the slides. 90 The side walls of the housing piece coact with the finger pieces in supporting the slides.

The parts are shown in their engaging position. When it is desired to release the 95 clamping member the slides are pushed toward the posts which raises the ends of the spring out of their engaging position and also opens the post slots of the binding member, so that the binding member can be removed from the post by a lateral movement. To engage the clutches, it is only necessary 100 to shift the slides outwardly which allows the ends of the spring to swing down to engaging position. The clamping member can 105 be pushed downward on the posts when the clutch is in engaging position as the tendency of such movement is to swing the ends of the clutch spring up. An upward pull on the clamping member causes the spring 110 to engage and bind or grip more tightly.

In the structure illustrated, I provide a

top cover 18, which is connected to the clamping member by the flexible hinge 19. The cover may, however, be any desired form and constitutes no part of my present invention.

5 My improved clutch mechanism is simple and economical in structure and very convenient to operate. I have illustrated and described my improvements in a simple and effective embodiment.

10 Although I am aware that considerable variation or modification in structural details is possible without departing from my invention, I desire to be understood as claiming the structure specifically in the form illustrated as well as broadly within the scope of the appended claims.

15 Having thus described my invention, what I claim is new and desire to secure by Letters Patent is:

20 1. In a binder, the combination of the posts; a clamping member comprising a bar and a channeled housing piece mounted on said bar, said bar and housing being transversely slotted to provide post openings, the top of the housing piece being longitudinally slotted; a clutch spring secured to said bar between the post openings thereof, the ends of the spring being adapted to engage the posts; clutch control slides arranged in said housing piece and having L-shaped slots adapted to register with the post openings when the slides are in their releasing position and to close the outer ends of said openings when in their locking position, said slides being formed of sheet metal folded, the lower arms of the slides being inclined downwardly and engaged under the ends of the clutch spring, the upper arms of the slides being provided with catch lugs coacting with the said post openings; and studs for said slides arranged through the said longitudinal slots in said housing piece and provided with finger pieces, the sides of the housing piece coacting with said studs and finger pieces to support and guide said slides.

25 2. In a binder, the combination of the posts; a clamping member comprising a bar and a channeled housing piece mounted on said bar, said bar and housing being transversely slotted to provide post openings, the top of the housing piece being longitudinally slotted; a clutch spring secured to said bar between the post openings thereof, the ends of the spring being adapted to engage the posts; clutch control slides arranged in said housing piece and having L-shaped slots adapted to register with the post openings when the slides are in their releasing position and to close the outer ends of said openings when in their locking position, said slides being provided with cams engaged under the ends of the clutch spring; and 30 studs for said slides arranged through the

said longitudinal slots in said housing piece and provided with finger pieces, the sides of the housing piece coacting with said studs and finger pieces to support and guide said slides.

3. In a binder, the combination of the posts; a clamping member comprising a bar and a channeled housing piece mounted on said bar, the ends of the top of the housing member being turned downwardly and terminating in attaching lugs arranged through said bar, said clamping member bar and housing being provided with post openings, the top of the housing piece being slotted; a clutch spring secured to said bar between the post openings to engage the posts; clutch control slides having cams engaging the ends of said clutch spring arranged in said housing piece; and studs for said slides arranged through said slots in said housing piece and provided with finger pieces, the sides of the housing piece coacting with said studs and finger pieces to support and guide said slides.

4. In a binder, the combination of the posts; a clamping member comprising a bar and a channeled housing piece mounted on said bar, said clamping member bar and housing being provided with post openings, the top of the housing piece being slotted; a clutch spring secured to said bar between the post openings to engage the posts; clutch control slides having cams engaging the ends of said clutch spring arranged in said housing piece; and studs for said slides arranged through said slots in said housing piece and provided with finger pieces, the sides of the housing piece coacting with said studs and finger pieces to support and guide said slides.

5. In a binder, the combination of the posts; a chambered clamping member having transverse post openings; a clutch spring secured between the post openings to engage the posts; clutch control slides arranged in said clamping member and having L-shaped slots adapted, when the slides are in their releasing position, to register with the post openings, said slides being formed of sheet metal folded, the lower arms of the slides being inclined downwardly and arranged under the ends of the clutch spring, the upper arms of the slides being provided with catch lugs coacting with the said post openings; and finger pieces for said slides.

6. In a binder, the combination of the posts; a chambered clamping member having post openings; a clutch spring secured between the post openings to engage the posts; clutch control slides arranged in said clamping member and having cams coacting with said clutch spring; and finger pieces for said slides.

7. In a binder, the combination of a post;

- a chambered clamping member having a post slot; a post clutch spring; a clutch control slide arranged in said clamping member and having L-shaped slot adapted to 5 register with the post slot when the slide is in its releasing position and to close the outer ends of said slot when in its clutch locking position, said slide being formed of sheet metal folded, the lower arm of 10 the slide being provided with a spring engaging cam, the upper arm of the slide being provided with a catch lug coacting with the said post slot; and a stud for said slide arranged through a slot in said clamping member and provided with a finger piece. 15
8. In a binder, the combination of a post; a clamping member having a post slot; a post clutch spring; and a clutch control slide having L-shaped slot adapted to register with the post slot when the slide is in its releasing position and to close said slot when in its clutch locking position. 20
9. In a binder, the combination of a post;

a clamping member having a post opening; a post clutch spring; and a clutch control 25 slide formed of sheet metal folded upon itself, one arm of the slide being provided with a spring engaging cam, the other with a catch.

10. In a structure of the class described, 30 the combination of a post, a clamping member having a laterally opening post slot adapted to receive said post, a post clutch spring, and a clutch control cam slidably mounted on said clamping member to contact with said spring, and adapted to close 35 said slot when in its clutch locking position.

In witness whereof, I have hereunto set my hand and seal in the presence of two 40 witnesses.

REINHOLD KRUMMING. [L. S.]
